UNITED STATES PATENT OFFICE.

WILLIAM CORCORAN, OF SEATTLE, WASHINGTON.

RAILROAD-TIE PLATE.

1,097,790.

Specification of Letters Patent.

Patented May 26, 1914.

Application filed November 4, 1913. Serial No. 799,077.

To all whom it may concern:

Be it known that I, WILLIAM CORCORAN, a citizen of the United States, residing at Seattle, in the county of King and State of Washington, have invented a certain new and useful Improvement in Railroad-Tie Plates, of which the following is a specification.

My invention relates to improvements in rail-road tie-plates one of which may be disposed between a rail and each of the rail-road ties of a curved portion of a rail-road more securely to maintain the two rails of such portion of the rail-road at a fixed distance from each other and to prevent a lateral displacement of both rails with respect to the rail-road ties, and the object of my improvement is to provide cheap and effective means for protecting the ties of a rail-road from wear and for preventing the rails from spreading apart or being laterally displaced on the ties by reason of the great strain against the outer rail of a curved portion of a rail-road due to the centrifugal force of a moving train. I accomplish this object by devices illustrated in the accompanying drawings in which—

Figure 1 is a view in side elevation of a tie-plate embodying my invention as it appears when in use on a rail-road tie; Fig. 2 is a plan view of the same; and Fig. 3 is a view in perspective of a modified form of the tie plate detached from the tie.

Referring to the drawings, throughout which like reference numerals indicate like parts, 22 is a metal plate that has both of its ends 25—25 bent substantially at right angles to the plane of the plate whereby such ends may lap over and engage with the ends of a rail-road tie 23.

My tie-plate is especially intended for use on curves where the centrifugal force due to the weight of a rapidly moving train tends to force the outer rail outwardly thus throwing a heavy pressure against the spikes that hold the outer portion of the flange of such rail and tending to cause such spike to crush the wood of the tie and permit the rail to move outwardly. The ends 25, 25 are spaced apart sufficiently to fit a tie of the usual standard length, however, in case the tie is longer than the plate 22, an end of such tie may be sawed off sufficiently to cause the tie to fit within such plate 22. If the tie be shorter than the distance between the turned end portions 25, 25 the ends of

the plate 22 may be allowed to project over the ends of the tie and if such short tie is located at a point where there is a curve in the road-bed it may be so positioned that the inner end 25 of the plate may engage with the inner end of the tie while the outer end of the plate 22 may be allowed to project outwardly past the outer end of the tie, the force tending to move the rails side-wise on a curve in the road-bed always acting outwardly thus tending to move the plate outwardly on the tie.

The tie-plate 22 is adapted to be secured to the side of a rail-road tie 23, by spikes or screws 24, and is further adapted to extend lengthwise of such tie, such plate 22 being provided with end pieces 25, 25 that are disposed at right angles to the plane of the plate 22, such end pieces being adapted to fit over and to be secured to the ends of the rail-road tie 23.

The upper edge of the plate 22, is formed with upwardly projecting lugs 26, 26 that are suitably spaced apart and adapted to engage the outside edge of the bottom flange of each rail 27 on a rail-road track, when the plate 22 is secured near the top side of the tie 23 as illustrated in Fig. 1, to prevent said rails from moving outwardly and spreading apart.

In cases where tie-plates are to be used on curves only, a tie-plate 28 as shown in Fig. 3 may be used, such tie-plate 28, being provided with upwardly projecting lugs 29, 29 and being formed to have only one end piece 30 that is similar to the end pieces 25 of the plate 22, said end pieces 30 being adapted, when the tie-plate 28 is in use, to engage with that end of a tie that is innermost on the curve thus operating to prevent the outer rail from moving outwardly.

Obviously the device may be constructed the full width of the tie throughout its length if so desired and various other changes in details may be resorted to without departing from the spirit of my invention or sacrificing any of its advantages.

What I claim is:

1. In a device of the class described, a tie-plate secured by suitable means to the side of a rail-road tie to extend lengthwise thereof and provided at each end with end portions that are bent at a right angle and disposed to engage with a portion of an end surface of such rail-road tie and further

provided with an upwardly projecting lug which is adapted by its position to engage with the base of a rail-road rail.

2. In a device of the class described, a tie-plate secured by suitable means to the side of a rail-road tie to extend lengthwise thereof and provided with an end portion that is bent at a right angle and disposed to engage with a portion of the surface of one end of said rail-road tie and further pro-

vided with an upwardly projecting lug which is disposed to engage with the base of a rail-road tie.

In witness whereof, I hereunto subscribe my name this 15th day of October A. D., 1913.

WILLIAM CORCORAN.
